UNITED STATES PATENT OFFICE.

EDWIN E. ARNOLD, OF PITTSBURGH, PENNSYLVANIA, ASSIGNOR TO REES MANUFACTURING COMPANY, OF PITTSBURGH, PENNSYLVANIA, A CORPORATION OF PENNSYLVANIA.

JACK HANDLE.

Application filed December 8, 1922. Serial No. 605,621.

To all whom it may concern:

Be it known that I, EDWIN E. ARNOLD, a citizen of the United States, and a resident of Pittsburgh, in the county of Allegheny and the State of Pennsylvania, have made a new and useful Invention in Jack Handles, of which the following is a specification.

This invention relates to jacks and more particularly to operating handles for those types of jacks that have a rotatable operating shaft (screw and worm drive jacks).

Anyone who has attempted to push a jack into position below the rear end of an automobile by means of the present-day handles which have a universal joint in their make-up knows that it is practically impossible.

A universal joint is necessary in order that the jack may be manipulated (to raise and lower the load) from a standing position.

An object of this invention is to produce a jack handle which has the necessary Cardan or universal joint in its make-up but which may be rendered sufficiently rigid to compel the jack when pushed by the handle to traverse a substantially straight line.

A further object is to produce a jack handle having a Cardan joint in its make-up which may be manipulated so as to be locked against pivotal movement about one of the joint pivots.

A further object is to produce a simple, relatively cheap and rugged jack handle which may be easily shifted or changed from a universal movement handle into a semi-rigid handle or one having pivotal movement about one pivot only.

A still further object is to produce a Cardan joint for use in jack handles, in which one of the pivots of said joint may be easily locked against pivotal movement and as easily released by movement of the jack handle toward and from the jack.

These, as well as other objects which will readily appear to those skilled in this particular art I attain by means of the device described in the specification and illustrated in the drawings accompanying and forming part of this application.

In the drawings Figure 1 is a view in elevation of a jack with a handle embodying this invention attached thereto. In this

view the Cardan joint entering into the make-up of the jack handle is shown extended for universal movement. Fig. 2 is a longitudinal sectional view of a portion of the handle, a portion of the rotatable jack shaft, the socket member and the link connecting the handle and socket members and forming the Cardan or universal joint. In this view the joint is shown extended for universal movement as in Fig. 1. Fig. 3 is a plan view of the parts shown in Fig. 2, but in collapsed position in which the handle member and link of the Cardan joint are locked against relative pivotal movement. Fig. 4 is a view similar to Fig. 2 of a modified form of device. In this view the parts are shown in locked position so that there is pivotal movement only about one axis of the Cardan joint. Fig. 5 is a view similar to Fig. 3 but of the modified form of device shown in Fig. 4, and in this view the parts are shown extended so as to have pivotal movement about both axes of the universal joint. Figs. 6 and 7 are plan and longitudinal sectional views respectively of a still further modified form of device. In Fig. 6 the device is shown collapsed to locked position and in this form when the joint is collapsed it is rendered rigid and without pivotal movement about either axis of the universal joint. In Fig. 7 the joint is shown extended for universal movement about both pivot axes. Fig. 8 is a view in section taken on line 8—8 of Fig. 7 looking in the direction of the arrows.

In all three forms of device, a socket member formed for attachment to the rotatable shaft of the jack is utilized.

A link is connected to the socket member by means of a pivot pin and to this link a handle member (the handle proper) is connected by means of another pivot pin. The axes of these pivot pins are disposed at right angles to each other and the axis of the pivot pin connecting the link to the socket member is disposed at right angles to the axis of the rotatable shaft of the jack.

The three parts (the handle proper, the socket member and the link) form a Cardan joint.

In all three forms of the device the socket member is preferably formed as shown in Patent No. 1,404,260 issued to the Iron City Products Company on January 24, 1922.

The form of device illustrated in Figs. 1, 2, and 3 is the preferred form and will be first described in detail.

The socket member 9 formed for detachable connection to the rotatable jack operating shaft 10 is provided with two ears 11 between which a link 12 is pivotally disposed at right angles to the axis of shaft 10. Handle member 14 has its inner end bifurcated and between the ears 15—15 thus formed, link 12 is pivoted by means of a pivot pin 16 having its axis disposed at right angles to the axis of pivot pin 13. The link 12 is provided with a longitudinally extending slot 17 of such width that pivot pin 16 will readily slide therealong. The heads 18 of pivot pin 16 are enlarged or formed in the nature of rivet heads.

Link 12 at the center of its end 19 is provided with a cylindrical projection 20 and the handle member is drilled so as to form a hole or pocket 21 for the reception of projection 20, the projection and the pocket co-operating to form a lock.

When the link and handle member occupy the position shown in Figs. 1 and 2, the Cardan joint is free or unlocked for universal movement, but when the handle member is slid longitudinally of link 12 to the position shown in Fig. 3 in which the projection 20 lies within pocket 21 the Cardan joint is rendered semi-rigid or locked against pivotal movement about pivot pin 16.

In order to push the jack into position by means of the handle, the Cardan joint is first collapsed by sliding the handle member longitudinally of the link to locked position. By turning the link until the axis of pivot pin 13 is horizontal, the jack may be pushed by means of the handle to the desired position. When the jack is in position the handle member may be pulled out of locked engagement with the link (the position shown in Figs. 1 and 2), and the jack operated from a standing position since the universal joint in this position is free.

In the form shown in Figs. 4 and 5 the handle member 14^a at its inner end is not only bifurcated so as to form ears 15^a but is provided with a box-like hood 22 adapted to fit end 19^a of the link 12^a.

Pivot pin 16^a is carried by ears 15^a of the handle member and rides within elongated slot 17^a formed in the link.

When the Cardan joint in this form of device is telescoped, as shown in Fig. 4 it is locked against pivotal movement about pivot pin 16^a by hood 22, but when extended as

shown in Fig. 5 it is free to be moved about both pivots.

In the form shown in Figs. 6 to 8 inclusive the link 12^b is slotted and pivot pin 16^b is carried by ears 15^b of the handle member 14^b. In this form the socket member 9^b is provided with a rectangular box-like portion 23 within which the outer ends 24 of ears 15^b are adapted to slide when the handle member is slid longitudinally of the link. It will be seen that in this form of device, all pivotal movement is prevented when the device is in collapsed position. This form of device obviously is not as efficient as either of the other forms as it will be necessary to have the handle member in line with the axis of the jack shaft in order to lock the universal joint against pivotal movement. It, however, is preferable to a device in which it is impossible to lock the universal joint against any pivotal movement.

Having thus described my invention, what I claim is:—

1. In a jack handle, a socket member; a handle member and a link pivotally connected to said members and relatively slidably lengthwise of one of said members to permit said member to be moved into a position in which it is locked against pivotal movement with relation to said link.

2. A structure according to claim 1 in which the link is connected to the socket and handle members by pivots having their axes disposed at right angles to each other.

3. A structure according to claim 1 in which the link and the member with which it is relatively slidable are provided with interengaging locking means.

4. A structure according to claim 1 in which the handle member and the link are constructed for relative longitudinal movement.

5. In a jack handle, a socket member, a handle member, a link connected to said handle and socket members by pivots and constructed for relative longitudinal movement with relation to one of said members for allowing the universal joint so formed to be longitudinally extended and collapsed and means for locking the members constructed for relative longitudinal movement against relative pivotal movement when the joint is collapsed.

In testimony whereof, I have hereunto subscribed my name this 1st day of December, 1922.

EDWIN E. ARNOLD.
